UNITED STATES PATENT OFFICE

RALPH V. L. HARTLEY, OF SOUTH ORANGE, NEW JERSEY

INTERNAL COMBUSTION ENGINE

Application filed January 3, 1927. Serial No. 158,449.

This invention relates to improvements in internal combustion engines and more particularly to the provision of means for providing an expansion ratio greater than the compression ratio. This variation is effected automatically during the proper portions of the operating cycle of the engine and in this way a higher operating efficiency is secured than heretofore.

A further object of the present invention resides in the provision of improvements in engines whereby the effective pressure peak in the combustion chamber may be reduced and this result is secured in such a way that the ratio of mean pressure or average pressure to maximum pressure is greater than heretofore.

A further object of the present invention resides in the provision of means whereby overall operating efficiencies of engines may be increased. This is effected by efficiently lowering the pressure peak in the engine so that lighter moving parts may be utilized than heretofore.

Another object of the present invention resides in the provision of an engine construction in which high power output may be temporarily secured in a simple manner. Such temporary high output is secured at the sacrifice of efficiency, but this is not objectionable when such greatly increased output is only derived for short periods as for starting a given load or the like.

A further object resides in the provision of an engine construction which is capable of relatively greater output at low speeds to the end that less changing of gears is necessary under varying conditions of operation.

Other and incidental objects reside in the provision of improved scavenging means for engines, thus making it possible to control the dilution of the charge independently of the compression ratio of the engine.

Another object of the present invention resides in the provision of an engine of such character that it is adapted for use with a variety of fuels and particularly such fuels as would heretofore cause excessive pressures which would cause damage to previous engines.

The engine also has utility in connection with modern fuels which afford higher compression ratios without attendant fuel detonation. My engine is adapted to utilize such fuels and increase the operating efficiency over present engines by affording a greater expansion ratio and also by permitting a greater compression ratio to be employed for an engine of given strength and structural design.

Another object resides in the provision of an engine construction in which the tendency to fuel detonation is reduced by providing that under those conditions of operation where it would otherwise be most likely to occur, combustion takes place at substantially constant pressure rather than at constant volume as in the present engines.

A further object resides in the provision of an engine construction in which the production of vibration in the engine and associated structures is reduced by restricting the sudden increase in pressure in the combustion chamber which normally accompanies the explosion of the charge.

Further and other objects and advantages will be hereinafter set forth in more detail in the accompanying specification and claims and shown in the drawings which by way of illustration, show what I now consider to be a preferred embodiment of the invention.

In the drawings:

Figure 1 is a vertical sectional view of my improved engine;

Figs. 2 to 5 inclusive, are detail views which show the relation in various steps of the cycle of operation.

Referring to the drawings in more detail, the engine has the conventional crank 10, connecting rod 11 and wrist pin 12 and valve gear comprising cam shaft 13 which 5 operates the usual inlet and exhaust valves 14 and 15 which are of conventional form (see Fig. 5). Any suitable well known ignition means such as spark plug 16 may be used:

10 According to the present invention, provision is made for first utilizing a relatively greater crank throw. This per se of course, would increase the expansion ratio for a given clearance volume. Provision is then 15 made for securing an expansion ratio which not only differs from the compression ratio but which is greater than the compression ratio whereby higher efficiencies and the other advantage heretofore mentioned are 20 secured.

The manner of securing these results will now be described.

I first provide a compound piston structure comprising an inner or main piston 20 25 operatively connected to the wrist pin with an outer or supplementary piston 21 telescoping the inner piston. The outer piston is provided with a lug 22 secured in any manner as by threading thereto, which slidably fits the lower and reduced portion of the inner piston and affords an annular air pocket space 23 therebetween. This pocket is provided with ports 24 which open into the interior of the inner piston or crank 30 35 chamber. As will later be explained, relative vertical motion occurs between the inner and outer piston and upon the suction stroke (see Fig. 2), the ports 24 are sealed off and thus afford an air cushion to prevent 40 the ring 22 from striking the flange portion of the inner piston. The outer piston is provided with a series of ports 25 around the periphery with intervening connecting web portions. Disposed in the inner piston 45 are a plurality of other ports 26 which upon all strokes connect the ports 25 with the interior of the inner piston and correspondingly to the crank case. As shown in Fig. 2 upon the suction stroke, the aforesaid 50 series of ports 25 and 26 afford a free opening to the pocket space 27 intermediate the head of the outer and inner pistons. This opening just mentioned is sealed off during 55 all other strokes.

60 The action of the compound piston during the various strokes will now be described.

Upon the suction stroke the inner piston is mechanically drawn down by the connecting rod. The pressure above the outer piston being relatively low, the outer piston lags relatively to the downward movement of the inner piston and finally assumes the position shown in Fig. 2 at the end of the 65 suction stroke. As an incidental advantage

the inertia of the outer piston upon the downward movement tends to continue its downward movement at the time the inner piston reaches the end of its down stroke, thereby effecting a slight additional induction of gas. This effect increases with engine speeds and thus tends to minimize the decreased quantity of fuel induced at high speed.

70 Upon the beginning of the compression stroke i. e. the beginning of the upward movement of the inner piston, the outer piston does not immediately move upward but lags until the space 27 is sealed off from the passage 25. Thereafter the gas or air in 75 27 is compressed and the head of the outer piston relatively approaches the head of the inner piston. It will be understood, 80 that the compression pressure of the charge in combustion space 28 will at all times 85 equalize with the pressure in space 27. Fig. 3 shows the relative position of the parts at the end of the compression stroke.

90 Ignition now takes place and the expansion stroke follows (see Fig. 4). Obviously the pressure above the upper piston is greater than the pressure in space 27 and the outer piston is forced down against the reaction of the air or gas in space 27. This space decreases on account of the higher 95 pressure above the outer piston until the pressure above and below the outer piston is balanced (see Fig. 4). As the expansion stroke proceeds the upper and outer pistons relatively recede from each other as 100 the explosion pressure falls. The pressure at the end of the expansion stroke is greater than atmospheric pressure and obviously the outer piston does not move out relatively 105 to the inner piston to an extent comparable with the position assumed upon a suction stroke in which case the pressure above the outer piston is less than atmospheric pressure.

110 When the exhaust valve opens the pressure above the upper piston falls. The pressure still exists below the upper piston and accordingly this piston moves out and scavenges the combustion space of the exhaust gases. The upper piston remains in this 11 position at the beginning of the suction stroke until its lowering movement is again initiated by the action of air cushioning in pocket 23. If desired the scavenging action can be dispensed with by dispensing with the entrapped gas space above the inner piston. In this case the inner piston would directly support the outer piston but an air cushion would be provided between the two pistons.

115 I also provide a relatively movable cylinder head for the combustion space. This improvement may be dispensed with or utilized as desired in connection with the piston action previously described, but in 120

practice it will be found advantageous, particularly, in explosive engines. As applied to Diesel engines the purpose of the novel head construction is rather to guard against the effects of high pressures resulting from faulty operation than to alter the cycle of normal operation. The piston devices find utility both in explosive engines and Diesel type engines. The piston devices previously described are not particularly suitable for two cycle engines of the explosive or Diesel type and in such cases the movable head devices can be utilized. Both the movable head and the piston arrangements can be used in combination in four cycle explosive or Diesel engines. The movable head can also be used in two cycle explosive or Diesel engines and the piston device itself can also be used in four cycle explosive or Diesel engines.

Above the combustion chamber, I provide a piston type head, generally designated at 30 and preferably but not necessarily of differential piston form including a smaller piston 31 and larger piston 32, 31 is directly acted upon by the pressure in the combustion space 28. Above the larger piston 32 is a chamber or space 33 which may be termed "a pressure storage chamber" which is preferably larger in volume as compared to the combustion chamber. The differential piston is preferably hollow so as to permit oil to be admitted through port 34 to both cool the piston and effect lubrication thereof. Gases of combustion are introduced into storage chamber 33 by means of a spring pressed valve 35 or other equivalent device. The gases pass from this valve to a passage 36 leading to the chamber 33 which passage is provided with any suitable control means as for instance, slide valve 37. In order to control the action of valve 37, I preferably provide a plunger member 38 which receives the action of gas pressure in chamber 33 and which is restrained against movement by a spring 39. The plunger 38 is also connected in any desired manner as by a linkage 40 with valve 37. The tension of spring 39 may be made adjustable in any suitable manner as by adjoined device 45.

The action of the head is as follows:

Before supplying fuel to the engine a pressure equal to or above the compression pressure must be built in chamber 33. This can be done by using the engine as a pump with the fuel supply cut off or any suitable means such as a hand pump can be used. This is necessary to prevent an accumulation of explosive mixture in chamber 33. Then upon operating the engine upon the explosion cycle the valve 35 opens and burnt mixture passes into chamber 33. Gas continues to accumulate in 33 until one of three conditions of equilibrium is reached. In

charge the pressure in chamber 33 becomes sufficient to close valve 37, after which it remains substantially constant. Under the first condition the pressure in the passage 36 then builds up to a value greater than that in 33 in approximately the ratio of the areas of the piston surfaces 32 and 31, after which valve 35 remains closed. On each succeeding explosion the pressure in the combustion chamber 28 rises to the value of that in passage 36. As it tends to rise further, the piston 30 moves upward under the action of the unbalanced forces so as to tend to maintain the pressure in 28 substantially constant. (See Fig. 4). As the combustion stops and the expansion stroke gets under way the pressure in 28 which would otherwise fall is maintained constant by the downward motion of piston 30 under the action of the pressure in chamber 33. This lowering action continues until the differential piston seats upon seat 42 or until it is arrested by the gas cushion above the seat. Thereafter expansion in the engine cylinder occurs in the ordinary way.

In the second condition the developed combustion pressure is more than enough to cause valve 37 to close but is below that which would cause movement of piston 30 when 37 is closed. Under this second condition the pressure in chamber 33 builds up until valve 37 closes after which it remains constant as before. The pressure in passage 36 builds up to the developed combustion pressure after which the valve 35 remains closed and the pressure remains constant. (The spring upon valve 35 is intended to exert no appreciable loading of the valve. It merely serves to seat the valve and is not intended to bring about a material loading thereof). The piston 30 then remains at rest throughout the explosion stroke. In the third condition the developed combustion pressure is less than the pressure at which valve 37 closes. The operation then differs from that in the second condition only in that valve 37 remains open and the pressure in chamber 33 as well as in passage 36 remains equal to the developed combustion pressure. It is obvious that in all except the first condition the operation is no different from that of the ordinary engine.

When the charge is changed as by altering the position of the throttle a new equilibrium is automatically established. If the charge is increased the mode of operation is identical with that already described. If it is decreased the pressures in chamber 33 and passage 36 remain at their original values but it will be readily seen that the desired operation with the new charge will not be altered thereby.

The above action allows the engine to operate at low loads with full efficiency and yet permits high peak pressures to be eliminated.

under high loads at which time the efficiency is relatively less important.

In order that the inertia of the differential piston 30 shall have as little influence on its motion as possible its weight should be kept as small as is consistent with its required strength. The amount of this inertia influence obviously increases with the engine speed. It will be understood, however, that at high speeds the amount of charge induced tends to fall off while the period of combustion becomes longer relative to the period of the expansion stroke. Both of these factors tend to limit the combustion pressure. Hence it is relatively less important that the piston 30 functions perfectly at high speeds. At low speeds there is time for a full charge to be drawn in and the combustion takes place before the expansion stroke has proceeded far enough to relieve the pressure appreciably. As a result with ordinary engines, the peak of the combustion pressure for a given throttle opening tends to be much greater at low speeds. Hence the effect of the piston 30 in reducing this peak makes possible the use of a wider opening of the throttle at low speeds than would otherwise be permissible, with the result that the power output at low speeds is correspondingly increased.

It will be understood that when the pressure peak is cut off, it is particularly desirable to have as great an expansion ratio as possible since the cutting off of the pressure peak brings about in the present embodiment an increased pressure at the end of the expansion stroke. It is accordingly desirable to utilize this pressure which can be readily done with the piston structure herein described.

It will be understood that the storage chamber 33 can, if desired, be common to all the cylinders of the engine. One or a multiplicity of valves 35-37 may be provided as desired.

What I claim is:

1. In an internal combustion engine in combination with a cylinder, a piston structure therein having a single operating connection to a crank means comprising air pockets which are sealed off and opened by the action of the piston structure associated with the said piston structure for automatically changing the volume ratio swept by said piston from one ratio to another upon compression and expansion strokes.

2. In an internal combustion engine, a cylinder, a main piston operatively connected to the crank, and a supplementary piston cooperatively associated with the main piston, and means comprising air cushions between the pistons and controlling ports in the pistons for automatically relatively displacing said pistons with respect to each other to afford one compression ratio and

a different and greater expansion ratio upon the cyclic operation of the engine.

3. The invention set forth in claim 2 in which air cushion means are provided intermediate the heads of the pistons for cushioning their relative action with respect to each other and in which means is provided for relieving the air pressure induced in said air cushioning means cyclicly upon each stroke.

4. An internal combustion engine including a compound piston structure with a main and supplementary piston, and means including porting valve means which are controlled for valving action by the main and supplementary pistons for utilizing the gas pressures upon said compound piston structure to secure variable volume ratios upon the compression and expansion strokes for the purpose described.

5. An internal combustion engine with a combustion chamber, a pressure storage chamber and a piston device therebetween, means to conduct gases from the combustion chamber to said storage chamber, and valve means controlled by the pressure in the storage chamber and irrespective of the pressure in the combustion chamber to cut off the flow of gases thereto upon determined conditions of pressure in the storage chamber.

6. An internal combustion engine with a combustion chamber, a pressure storage chamber and a piston device therebetween, means to conduct gases from the combustion chamber to the storage chamber, and a dual valve means intermediate the combustion chamber and the storage chamber, one valve means having provisions to cut off the back flow of gases to the combustion chamber and the other valve means having provisions to cut off the flow of gases to or from the pressure chamber, said last mentioned valve means being controlled to be maintained in closed condition irrespective of the relative pressure differences in the combustion chamber and pressure storage chamber.

7. An internal combustion engine having a combustion chamber and a pressure storage chamber and a differential piston therebetween, and means for admitting a cooling medium to the interior of said piston device for cooling the latter, said means having provisions for keeping the cooling medium separate from the gases which act upon the differential piston and which come from the pressure storage chamber.

8. An internal combustion engine having a combustion chamber and a pressure storage chamber and a hollow differential piston therebetween, and means for admitting lubricant to the hollow portions of said piston during back and forth movements thereof.

9. An internal combustion engine having a plurality of engine cylinders each with a combustion space, a pressure storage chamber common to a plurality of said cylinders, and piston devices between said pressure storage chamber and the combustion space of each cylinder, each piston device being at all times during the cycle of the operation of the engine subject to the pressure in the common pressure storage chamber.

10. In testimony whereof I hereto affix my signature.

RALPH V. L. HARTLEY.
